WIRING DEVICE
Harvey Hubbell, Southport, Conn., assignor to Harvey
Hubbell Incorporated, Bridgeport, Conn., a corporation
of Connecticut.
Filed June 10, 1966, Ser. No. 556,671
4 Claims. (Cl. 339—196)

ABSTRACT OF THE DISCLOSURE

An improved wiring device having a metal shell with inwardly deformed locking portions and an insulating member disposed in the shell, the insulating member carrying rotatable locking fasteners which are slightly rotatable to coat with respective locking portions to hold the insulating member in the shell.

This invention relates to improvements in electrical wiring devices, and more particularly to providing in them improved means for assembling the usual insulator portion to the usual metal shell of an electrical wiring device.

In most electrical wiring devices, such as connectors of the connector body and cap type, the usual screws for securing the two usual parts of the assembly, viz., the insulator portion and metal shell, together extend through the insulator portion and are anchored in taps in a back wall of the metal shell. In so doing, they pose problems in the electrical wiring area of the wiring device in that they occupy room, as well as necessitate generous space allowances for purposes of insuring sufficient strength of the insulator portion and providing a longer electrical leakage path from live electrical current carrying elements to the dead metal assembly parts.

Accordingly, it is a primary object of this invention to provide an improved electrical wiring device which does not require the usual securing screws to assemble the device.

It is another object to provide an electrical wiring device which allows greater flexibility in the design of the electrical connections.

It is a further object to provide an improved electrical wiring device which may be quickly and readily assembled and disassembled.

To accomplish these objects, in one form a wiring device is provided which comprises: a metal shell member having a plurality of restricted locking portions; an insulating member disposed in the shell member; and a plurality of restricted fasteners carried by said insulating member and arranged to coat selectively with the locking portions of the shell in response to slight angular turning to hold the insulator and the shell together.

Other objects and further details of that which I believe to be novel and my invention will be clear from the following description and claims taken with the accompanying drawing, wherein:

FIG. 1 is an elevational view of a complete electrical connector cap constructed in accordance with this invention and showing the improved fastening means in phantom lines;

FIG. 2 is a bottom plan view of the FIG. 1 connector cap showing the fasteners in solid lines in locking position and showing in phantom lines one of the fasteners rotated to an unlocking position;

FIG. 3 is a sectional view taken substantially along line 3—3 of FIG. 2 showing the fastener in locked position;

FIG. 4 is a sectional view taken substantially along the line 4—4 of FIG. 3;

FIG. 5 is an isometric view of the fastener;

2

FIG. 6 is an isometric view of a modification of the fastener;

FIG. 7 is a sectional view similar to that of FIG. 3, showing the locking action of the modified fastener and metal shell; and

FIG. 8 is a fragmentary side elevational view showing in detail the modified locking portion of the shell.

With reference to the drawing, one form of electrical wiring device incorporating my invention is shown in FIG. 1 and comprises a metal shell sheathed connector cap 10 having a cup-shaped metal shell within which is seated a two-part body 12, 14 of suitable electrical insulating material. An electrical cable 16 is held in place and strain relieved by a suitable cable clamp 18, and its bared electrical wires are introduced to the wiring area of the device where they are wired to the terminals of contact blades 20.

The metal shell has a generally cylindrical wall 11 and one planar end wall 13. The wall 11 is provided with a plurality of arcuately inwardly deformed portions 22 which are sheared from the wall 11 of the shell, resulting in sheared edges as at 24. The portions 22 serve to position the two-part insulator 12, 14, as well as to coat with the headed fasteners 26 to effect the desired locking action.

The insulator body comprises two generally cylindrical sections 12 and 14, and section 12 is provided with positioning cutouts 28 on its periphery to allow it to be seated in the metal shell and be positioned by the inwardly deformed portions 22. The insulator section 12 is further provided with a plurality of axial openings 30 which receive the shafts 36 of the fasteners 26. The openings are large enough to allow the fastener shafts to rotate freely, and are located radially inwardly from the cutouts 28 and thereby serve to locate the fasteners 26 adjacent the deformed portions 22 of the metal shell. The insulator section 12 has recesses 32 that communicate with openings 30 and within which the heads of the fasteners 26 may rotate. Insulated section 14 is provided with recesses 34 for housing securing washers 42, 44 that are mounted on shafts 36.

The fasteners 26 comprise the referred-to shaft 36 which is rivet-like, and a slotted head 38 having an eccentric wedge-shaped camming head portion 40. When assembled on the insulator section 12, the fasteners 26 are mounted to be selectively rotated, but firmly secured and precluded from any vertical motion by the downward force of spring washer 42 transferred through plain washer 44 to the splayed retaining end 46 of the rivet shaft 36.

In use, the insulator section 14 is placed in the shell, and the insulator section 12 with the fasteners 26 attached thereto is seated in the shell adjacent section 14. It will be understood that these sections cooperate in a known way to define chambers for the contact-terminal means and cable leads. In order to permit assembly, the fasteners are adjusted to their positions represented by the phantom lines in FIG. 2. A screwdriver or other suitable tool is used to engage the slotted heads 38 and to rotate the fasteners. After the section 12 is mounted in the shell, the heads 38 are rotated toward their solid line position. This rotation causes the eccentric camming head portions 40 to underlie sheared edge 24 of the inwardly deformed portion 22. As the fastener is rotated into locking position, the wedge shape of the cam head portion 40 causes the insulation sections 12, 14 to be biased against shell wall 13 and rigidly secured in the metal shell. In order to disassemble the insulation sections and the shell, it is only necessary to rotate the fasteners back to their unlocking position. This action and the angular extent of rotation of the fastener heads can be readily seen

in FIG. 2 by comparing the solid and phantom line positions.

FIGS. 6 and 7 illustrate a modified form of the fasteners and shell of the invention. The basic features of the modified wiring device are similar to the first one described and similar parts are given similar numerals with a prime (') added. The modified construction allows the fasteners to positively engage the deformed portions of the metal shell with a snapping action and effect a positive lock that cannot be released by vibration.

The modified fastener 26' comprises a shaft 36' and a slotted head 38' having an eccentric wedge-shaped head portion 40'. On the upper surface of the portion 40' a wedge-shaped camming rib 48 is formed with an inclined face 50 formed at one side. The inwardly deformed portions 22' of the metal shell are provided with rib receiving slots 52 cut into the sheared edge 24'.

When assembled, a spring washer 42' is interposed between the head portion 40' of the fastener and the insulation section 12'. The fastener is retained in place by a plain washer 44' and the splayed retaining end 46' of the rivet-like shaft 36'. The insulation sections 12', 14' are seated within the metal shell, and a screwdriver may be used to turn the head 38' of the fastener 26'. As the fastener is rotated, the inclined face 50 of rib 48 acts as a lever to cam the fastener downwardly against the upward force of the spring washer 42', which positively snaps the fastener upwardly when the camming rib 48 is moved to a position under the rib engaging slot 52. When so positioned, a positive lock is effected which cannot be jarred loose. To effect disassembly, it is only necessary to reversely rotate the fastener 26' while vertically depressing the head 38' to disengage the rib 48 out of the slot 52.

It is understood that the present disclosure has been made only by way of example, and that numerous changes in details of construction and the combination and arrangement of parts may be resorted to without departing from the spirit and scope of the invention as hereinafter claimed.

What I claim as new and desire to secure by Letters Patent of the United States is:

1. In an electrical wiring device: a shell; at least one locking portion formed in said shell; an insulating member disposed in said shell and fixedly positionable therein, said insulating member provided with at least one positioning cut-out which clears said locking portion and allows said insulating member to be inserted into said shell; and at least one fastener carried by said insulating member and arranged to coact selectively with said locking portion of said shell to secure said insulating member in said shell in response to slight angular turning of said fastener.

2. The electrical wiring device defined in claim 1 where-
in said insulating member is provided with a cutout por-

tion arranged to receive an eccentric head portion of the fastener and allow said head portion to rotate therein.

3. In an electrical wiring device: a shell comprising a cap having an end wall and a cylindrical wall; at least one locking portion formed in said shell, said locking portion being located in said cylindrical wall and comprising a radially inwardly deformed portion; an insulating member disposed in said shell and fixedly positionable therein, said insulating member having at least one positioning cut-out which clears said locking portion and allows said insulating member to be inserted into said shell; and at least one fastener carried by said insulating member and arranged to coact selectively with said locking portion of said shell to secure said insulating member in said shell in response to slight angular turning of said fastener, wherein said fastener comprises a rotatable rivet-like shaft having a wedge-shaped eccentric head portion which is arranged to underlie said locking portion and said eccentric head portion is provided with means by which the said fastener may be rotated, and wherein said insulating member is also provided with a cut-out portion arranged to receive said eccentric head portion to allow said head portion to rotate therein.

4. In an electrical wiring device: a shell comprising a cap having an end wall and a cylindrical wall; at least one locking portion formed in said shell, said locking portion being located in said cylindrical wall and comprising a radially inwardly deformed portion having a slot therein; an insulating member disposed in said shell and fixedly positionable therein; at least one fastener carried by said insulating member and arranged to coact selectively with said locking portion, said fastener comprising a rotatable rivet-like shaft having an eccentric head portion with a wedge-shaped camming rib disposed upon its face arranged to be selectively positionable within said slot; and spring means disposed so as to bias said fastener upwardly thereby allowing the said fastener to have vertical downward motion, whereby said insulating member may be secured in said shell in response to slight angular turning of said fastener.
